Patented Sept. 5, 1967

208,495

SHOE BRAKE DRUM FOR PAPER ROLLS OR THE LIKE

Lawrence A. Moore, King of Prussia, Pa., and Edward J. Klaczkiewicz, Wilmington, Del., assignors to Beloit Corporation, Beloit, Wis., a corporation of Wisconsin

Filed Apr. 4, 1966, Ser. No. 1,761

Term of patent 14 years

(Cl. D55—1)

Fig. 1

Fig. 2

FIGURE 1 is a perspective view of a shoe brake drum for paper rolls or the like embodying the design features of the present invention; and

FIGURE 2 is a perspective view rotated 90° of the shoe brake drum for paper rolls or the like shown in FIGURE 1.

The rear of the structure shown in FIGURES 1 and 2 is substantially identical in appearance to the front portion shown on the drawings.

We claim:

The ornamental design for a shoe brake drum for paper rolls or the like, as shown and described.
